(57) CLAIM

The ornamental design for a four-sectioned binder for holding cards, as shown and described.

DESCRIPTION

FIG. 1 is a top perspective view of a four-sectioned binder for holding cards showing my new design, wherein the binder is in a fully closed configuration and secured with an elastic band;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is another top perspective view of the four-sectioned binder for holding cards, shown in a half open configuration where the two left sections are closed and the two right side sections are open to show the multi-card holder sleeves;

FIG. 8 is a top plan view thereof;

FIG. 9 is a front elevation view thereof;

FIG. 10 is another top perspective view of the four-sectioned binder for holding cards, shown in a fully open configuration;

FIG. 11 is a top plan view thereof;

FIG. 12 is a front elevation view thereof;

FIG. 13 is a front elevation view of the four-sectioned binder for holding cards thereof, showing a multi-card holder removed in order to show aspects of the design that are not otherwise apparent; and,

FIG. 14 is an enlarged front elevation view thereof, of the circled portion thereof in FIG. 13.

The contrast in shading techniques between straight occasionally broken line shading and stipple shading represents a contrast in appearance as shown.

The evenly spaced broken lines are directed to environment and are for illustrative purposes only while the dot-dash broken lines are for the purpose of identifying the partially
